UNITED STATES PATENT OFFICE

1,997,475

RAILWAY SIGNAL SYSTEM

Chauncey G. Suits, Schenectady, N. Y., assignor
to General Electric Company, a corporation of
New York

Application November 18, 1933, Serial No. 698,629

11 Claims. (Cl. 246—34)

My invention relates to railway signal systems and particularly to those of that type in which a signal is actuated in response to the passage of a car or train along a portion of the railway track.

- 5 In certain common railway signal systems, a voltage is applied across the rails of the track at one end of an insulated section, termed a block, and this voltage energizes a relay connected across the rails at the other end of the section.
- 10 The presence of a train in the section decreases the resistance between the rails and the resulting decrease in voltage at the relay causes the relay to operate. It has always been a problem to sufficiently reduce the resistance between the rails
- 15 by the presence of a train to cause the operation of the relay to be positive. This difficulty has become more acute recently because of the development of light rolling stock, such as gas electric cars, and is particularly serious where rubber
- 20 tired vehicles are used. Where the operation of the relay depends upon the change in resistance between the rails as in the present systems, a difficulty occurs because the resistance between the rails may change from two causes: first, the
- 25 presence of a train in the section, and second, the change in leakage resistance between the rails. In practice both of these factors have a total variation of the order of one hundred-fold.

It is the object of my invention to provide an improved system which avoids the difficulties of the present system and insures the proper operation of the signal relay notwithstanding wide variations in the resistance between the rails due either to a train or to leakage.

- 30 In accordance with my invention the operation of the signal relay is dependent not only upon a change of resistance between the rails but upon the rate of change of that resistance. Thus my invention differentiates between the change in resistance due to a train, which is sudden, and the change in resistance due to leakage, which is relatively slow. To effect this result I provide means for regulating the voltage across the rails which regulating means has a predetermined time delay characteristic. The amount of delay is such that a substantially constant voltage is maintained across the rails in spite of changes in leakage resistance but when a train enters the
- 35 section producing a sudden drop in resistance between the rails sufficient time elapses before the regulating means becomes completely effective to restore the voltage to allow the relay to operate.
- 40 Also I provide the regulator with means whereby
- 45 after the relay operates in response to a train en-

tering the section the regulator regulates the voltage to a different value than before.

5 My invention will be better understood from the following description taken in connection with the accompanying drawing, and its scope will be pointed out in the appended claims.

10 Referring to the drawing, Figs. 1 and 2 are circuit diagrams showing the preferred and a modified form of my invention; and Fig. 3 is a diagram showing relative values of various voltages across the rails.

15 In Fig. 1 of the drawing 1 represents a section or block of railway track comprising the rails 2 and 3 between the insulating joints 5 and 6. At one end of section 1 I have shown the relay 7 connected across the rails, which relay has back contacts 8 connected with any suitable signal circuit 9, it being understood that when there is no train in the section the relay is energized or pulled up as illustrated. At the other end of the section I have shown means for applying a rectified voltage across the rails. This means comprises the transformer 10 whose primary connects with the source of alternating current supply 11, which for example may be a 110 volt, 60 cycle constant potential source, through the saturable core reactor 12, which is provided with the saturating winding 13. The secondary of transformer 10 connects with the rails 2 and 3 through the full wave rectifier 14 and the limiting resistor 15. Rectified current is supplied to the saturating winding 13 of reactor 12 from the source 11 through the transformer 16, the electron discharge device 17, and the limiting resistor 18. The electron discharge device 17 is shown as a tube having two similar anodes 20 and 21 which connect with the opposite ends of the secondary of transformer 16, and as having a cathode 23 provided with the heater 24. The saturating winding 13 connects at one side through resistor 18 with the midpoint of the secondary of transformer 16 and at the other side connects with the cathode 23. The cathode heater 24 is connected to be supplied by alternating current from the source 11 through the limiting resistor 25. With this apparatus rectified current is supplied from the source 11 to the saturating winding 13 in accordance with the temperature of the cathode 23, it being understood that the reactance offered by the reactor 12 is governed by the degree of saturation of its core produced by the winding 13 and as long as the temperature of the cathode 23 remains constant the reactance of reactor 12 also remains constant and a constant voltage is applied across the rails of the track if the re- 55

sistance between the rails does not change. In order that the voltage between the rails may be regulated for a substantially constant value, notwithstanding changes in resistance between the rails, I have provided the saturable core reactor 27 which is connected in shunt with the cathode heater 24. Reactor 27 is provided with the saturating winding 28, which connects through the resistor 29 with the rails 2 and 3 whereby the reactance offered by the reactor 27 and hence the current supplied to the cathode heater 24 varies in accordance with the voltage across the rails. Inasmuch as the temperature of the cathode 23 does not respond immediately to changes in the current supplied to the heater thereof but involves a certain time delay in responding to changes in heater current, it will be seen that with the above described apparatus changes in the voltage supplied to the rails in response to changes in resistance across the rails, such as that due to a train entering the section, is made only after a definite time delay. This delay is sufficient to enable the relay to operate before the voltage between the rails is restored.

Inasmuch as the signal relays commonly employed for operation in response to changes in track resistance have a pull-up or opening voltage somewhat higher than their drop-out or closing voltage, I have provided the regulator with means whereby after relay 7 operates to close the signal circuit in response to the presence of a train in the section, the voltage across the rails is regulated to a different value. In the present case this new value is somewhat higher than before but is lower than the pull-up or opening voltage of the relay. For this purpose the relay is provided with the front contacts 30 which connect with opposite ends of the resistor 29 so that when there is no train in the section and the relay is pulled up, the resistor is short circuited, and when the relay drops out due to a train entering the section the short circuit is opened. Since resistor 29 is included in the saturation circuit of reactor 27 it will be seen that the cathode 23 will operate at either one of two temperatures resulting in the application of either one of two voltages to the rails depending upon the position of the relay.

The operation of the apparatus disclosed by Fig. 1 is as follows. When there is no train in the section or block 1, relay 7 is pulled up as represented in Fig. 1. When a train enters the section the resulting decrease in resistance between the rails causes a sudden decrease in voltage across the rails. This decrease in voltage is sufficient to cause the relay 7 to operate, that is, to drop out, whereby the back contacts 8 close the circuit 9 and the front contacts 30 are opened. Referring to Fig. 3, the regulated voltage when no train is in the block may be that shown at A while the relay drop-out voltage represented by B may be slightly lower than A. The aforementioned decrease in voltage across the rails to which is added the voltage drop now across resistor 29 causes a decrease in saturation of reactor 27. In accordance with the well known principles governing the operation of saturable core reactors, this reactor now offers a greater impedance to the flow of current therethrough and since the reactor is in shunt with the heater 24, a greater current is supplied to the heater. The resulting increase in temperature of the cathode 23 causes a greater electron flow between the cathode and the anodes 20 and 21 whereby the saturation of re-

actor 12 is increased. The reactance offered by this reactor accordingly decreases, and hence the voltage applied across the rails increases. Because of the time required for the cathode 23 to change its temperature, the change in voltage applied to the rails takes place only after a predetermined time delay, which time is sufficient for the relay 7 to operate. Relay 7 having operated and through its back contacts having opened the shunt circuit about resistor 29, the apparatus now regulates the voltage applied to the rails to a new and higher value, which value is somewhat below the relay pull-up-voltage. Referring again to Fig. 3 the new regulated voltage applied to the rails may be that represented at C, while the relay pull-up voltage may be that represented at D. When the train leaves the section the resistance between the rails suddenly increases whence the relay is pulled up to open the signal circuit 9 and to close the shunt circuit about resistor 29. The apparatus now regulates the voltage applied across the rails to the original lower value but this regulation is effected only after a predetermined time delay governed by the time required for the change in temperature of the hot cathode. Where the change in resistance between the rails takes place slowly, as for example, that due to leakage, the above described regulating means is sufficiently rapid in its operation to preserve a substantially constant voltage between the rails. It will be seen therefore, that the resistance between the rails may vary through wide ranges without operating the signal relay provided these changes take place slowly. However, if even a relatively small change in resistance between the rails takes place suddenly, as for example, when a car or train of relatively light construction enters the section, the relay will respond to give a signal.

In the modified form of my invention illustrated by Fig. 2, I supply alternating current to the rails from the source 11 through the limiting resistor 35. In this case the voltage across the rails is controlled by the saturable core reactor 36 which, being connected across the rails, acts as a variable shunt, so that the voltage across the rails is that of the supply 11 minus the voltage drop across resistor 35. In this case the current supplied to the saturating winding 37 of reactor 36 is that which passes the two-element electron discharge tube 38 which not only controls the current value in the saturating winding but also rectifies the current. The tube 38 has a hot cathode 39 which is included in the series non-linear resonant circuit 40 comprising the self-saturating reactor 41 and the capacitor 42. This non-linear resonant circuit is energized by the secondary of transformer 43 whose primary connects across the rails. The signal relay 44 is similar to relay 7 in Fig. 1 except that in addition to the back contacts 8 which control the signal circuit 9 it includes a pair of front contacts 45 which connect circuit 49 with one end of the secondary of transformer 43 and includes a second pair of rear contacts 46 which connect circuit 40 with an intermediate point 47 of the same secondary winding.

The operation of the modified form illustrated by Fig. 2 is as follows. When there is no train in the section, the relay is energized to hold the signal circuit open and to include the whole of the secondary winding of transformer 43 in the non-linear circuit 40, as illustrated. The volt-

age applied to circuit 40 is such that the circuit is now in a resonant condition, hence the current supplied to the cathode 39 is a maximum and the current passing the tube 38 and the saturating winding 37 is a maximum. Reactor 36 accordingly being saturated offers a minimum impedance across the rails and the voltage across the rails therefore is a minimum which value may correspond to that represented at A in Fig. 3.

10 When a train enters the section the resulting decrease in resistance between the rails causes the signal relay 44 to drop out and close the signal circuit 9. In so doing the relay changes the connections of the circuit 40 to include a fractional part only of the secondary of transformer 43. The decrease in voltage now applied to the non-linear resonant circuit 40 causes this circuit to become non-resonant, and the resulting decrease in current thereof allows the cathode 39 to become cooler. Less current therefore, is supplied to the saturating winding 37 and reactor 36 increases the impedance it offers to the shunt circuit across the rails, wherefor the voltage across the rails increases. This increase value 25 may be that shown at C in Fig. 3. Because of the time required for the hot cathode 39 to change its temperature, the change in voltage between the rails takes place only after sufficient time has elapsed for relay 44 to operate. Since the 30 relay has changed the connections of circuit 40 to include a portion only of the transformer secondary the apparatus now regulates the voltage between the rails to a different or higher value than before. When the train leaves the section 35 the resulting increase in voltage between the rails causes relay 44 to pick up and open the signal circuit 9 thus returning to its original position as illustrated. The circuit connections of the non-linear resonant circuit 40 are now returned to 40 their original form and the apparatus after a predetermined time interval again regulates the voltage between the rails to the original value which may be that shown at A in Fig. 3. As described in connection with Fig. 1, a gradual 45 change in resistance between the rails does not affect the signal relay since the apparatus is able to regulate the voltage across the rails to preserve a substantially constant value.

While I have shown the various saturable core reactors described above as having a three-legged core structure, it will be understood that if desired each of these reactors may comprise two similar transformers connected as shown for example in my Patent 1,885,155 of November 1, 50 1932.

55 I have chosen the particular embodiments described above as illustrative of my invention and it will be apparent that various other modifications may be made without departing from the spirit and scope of my invention which modifications I aim to cover by the appended claims.

What I claim as new and desire to secure by Letters Patent of the United States, is:—

1. A railway signal system comprising means 60 for applying a voltage across the rails of a track, an electromagnetic relay connected to be responsive to the voltage across said rails and a delayed action regulating means for restoring the voltage across the rails in response to a sudden decrease in resistance therebetween, the delay in action of said regulating means being sufficient to enable the relay to operate.

2. A railway signal system comprising means 65 for applying a voltage across the rails of a track, a signal relay connected to be responsive to the

voltage across said rails and means for regulating the voltage applied to the rails with a predetermined time delay, said means being constructed to regulate the voltage to a different value in response to the operation of said relay.

3. A railway signal system comprising means for applying a voltage across the rails of a track, time delay regulating means for regulating the voltage applied to the rails, a relay connected across said rails and means responsive to an 10 operation of said relay for causing the regulating means to regulate to a higher value.

4. A railway signal system comprising means for applying a voltage across the rails of a track, means for regulating the voltage applied across 15 the rails after a predetermined time delay, a relay connected across said rails and means responsive to the operation of said relay for causing the regulating means to regulate the voltage to a new value, said value being higher than the previous value but lower than the value at which 20 said relay operates.

5. A railway signal system comprising means for applying a voltage across the rails of a track, means responsive to a decrease in resistance 25 across the rails for regulating the applied voltage after a predetermined time delay, a relay connected across said rails and having contacts for controlling a signal circuit and having other contacts, and means connected with said other contacts for causing the regulating means to regulate the applied voltage to higher value.

6. A railway signal system comprising means for applying a voltage across the rails of a track, a relay connected across said rails and constructed 35 to operate in response to a sudden drop in voltage across the rails, regulating means responsive to the operation of the relay for restoring said voltage and means controlled by said relay for causing the regulating means to regulate the voltage 40 to a higher value.

7. A railway signal system comprising means for applying a voltage across the rails of a track, regulating means therefor including an electron discharge device having a hot cathode whose 45 temperature controls the rate of regulation, means responsive to the voltage across the rails for causing the regulating means to regulate to produce either one of two different voltages and a relay connected across said rails for determining for 50 which voltage the regulating means shall operate.

8. A railway signal system comprising means including a series reactor for supplying a regulated voltage across the rails of a track, an electron discharge device having a hot cathode arranged to control the reactance of said reactor, means for supplying current to heat said cathode, a reactor controlled by the voltage across said rails for varying said current, a signal relay connected across said rails and means controlled 60 by said relay for changing the current supply to said cathode.

9. A railway signal system comprising means for applying voltage across the rails of a track, a signal relay connected to operate in response to a decrease in voltage across the rails and means responsive to the operation of said relay for restoring the voltage across the rails.

10. A railway signal system comprising means for applying voltage across the rails of a track, a signal relay connected to operate in response to a decrease in voltage across the rails and means responsive to the operation of said relay for raising the voltage across the rails to a value higher than the original value thereof.

11. A railway signal system comprising means for applying a voltage across the rails of a track at one portion thereof, a relay connected to operate in response to a decrease in voltage across said rails of the track at another portion thereof and means responsive to a slow decrease in resistance

between the rails for maintaining a substantially constant voltage therebetween at said other portion and responsive to the operation of said relay for producing an increase in voltage across the rails.
